UNITED STATES PATENT OFFICE.

FREDERICK H. WEEKS AND CHARLES D. WEEKS, OF AKRON, OHIO; SAID CHARLES D. WEEKS ASSIGNOR TO SAID FREDERICK H. WEEKS.

MACHINE FOR CUTTING WEIGHT-POCKETS IN WINDOW-FRAMES, &c.

1,083,473.

Specification of Letters Patent.

Patented Jan. 6, 1914.

Application filed December 24, 1910. Serial No. 599,236.

To all whom it may concern:

Be it known that we, FREDERICK H. WEEKS and CHARLES D. WEEKS, of Akron, in the county of Summit, and in the State of 5 Ohio, have invented a certain new and useful Improvement in Machines for Cutting Weight-Pockets in Window-Frames, &c., and do hereby declare that the following is a full, clear, and exact description thereof.

10 The object of our invention is the production of a machine of simple construction by which the operations of cutting the weight pockets and rabbeting or dadoing the stiles of window frames to receive the 15 sills may be conveniently and expeditiously and, therefore, inexpensively performed, and to this end and others, of perhaps less importance that will appear hereinafter, our invention consists in the machine having the 20 construction substantially as hereinafter specified and claimed.

Referring to the accompanying drawings—Figure 1 is a perspective view of a machine embodying our invention; Fig. 2 25 is a top plan view; Fig. 3 is an end elevation; Fig. 4 is a longitudinal section thereof; Fig. 5 is a longitudinal section of the saw mandrel; and Fig. 6 is a detail view in perspective of one of the dado cutters.

30 The machine we illustrate as an embodiment of our invention is constructed and organized so that it will cut the parallel longitudinal slits for the sides of a sash weight pocket, and then make the cross-cuts 35 at the ends to complete the pocket, and dado or rabbet the stile for the reception of the ends of the sill, and perform these last two operations simultaneously on two stiles. It will be apparent that the simultaneous operations conduce to expedition in the performance of the work, mean accuracy in the performance of the work, and the performance of the various operations mentioned by one machine means saving of cost 40 of machinery and space in the shop, together with reduced cost of labor of production.

Proceeding now with a particular description of the machine illustrated, it has 50 a suitable frame whose principal parts are two side members 10 having bearings for main shaft 11, provided with fast and loose pulleys 12 and 13. On the main shaft 11 is a worm 14 meshing with a worm wheel 15 on shaft 16 extending longitudinally of the

machine at right angles to the main shaft 11. Near one end, the longitudinally extending shaft 16 has a drum 17 from which a cord or chain 18 runs to the lower transverse member of a vertically reciprocating yoke 19, and by the winding of the cord or chain on said drum 17 the said reciprocating yoke 19 is lifted at which time said drum 17 is clutched or connected to said shaft 16, and, on the disconnection of said drum 17 from said shaft 16, said reciprocating yoke 19 descends by gravity, supplemented by a spring or weight if need be, and retarded in descent by a dashpot 91, composed of an air or liquid chamber provided with suitable 60 valve and piston. The clutch connecting said drum 17 and said shaft 16 consists of a pin 161 on said shaft 16 that engages an internal shoulder 171 on said drum 17 and by the longitudinal movement of said shaft 16, the engagement and disengagement of 65 said pin 161 and said shoulder 171 are effected. To move said shaft 16 longitudinally to disengage said pin 161 and said shoulder 171 and at the same time disconnect said worm wheel 15 from said worm 14, we provide a pair of collars 162 on said shaft 16 engaged by a cam 163 on a lever 164 pivotally mounted on a shaft 34 hereinafter referred to, the lever 164 having a 70 handle 165 to impart longitudinal movement to said shaft 16 in both directions. The yoke 19 has parallel vertical side members in the form of heavy rods which pass through guides 20 in a frame 21 extending 75 between and bolted to the ends of the frame sides 10. At its upper end, said yoke 19 has bearings for a horizontal shaft or mandrel 22, to which are secured a pair of circular saws 23 by means of which the longitudinal 80 slits in the stiles are made. Said saws may be adjustable toward and from each other on said mandrel 22 to vary the width of the pocket to be cut in the stiles, and if desired one of the saws may be removable so that 85 the remaining one may be used for sizing or other purposes.

For revolving the saw mandrel, it is provided with a band pulley 24 which is secured to said mandrel 22 by providing a 90 threaded portion 240 on the mandrel on which is screwed a nut 241 that is seated in a socket in the side of the said pulley 24, the thread being in a direction which by the revolution of said pulley 24 to revolve 95

said mandrel 22, causes a tendency of said pulley 24 to press said saws 23 against collars fixed on said mandrel 22 and thus the pulley and saws are securely mounted on the mandrel 22 and yet the removal of said saws 23, when necessary, is easily accomplished by a simple unscrewing operation.

From the band pulley 24 an endless band 25 runs to a pulley 26 on a short shaft journaled in the outer end of an arm or frame 27 that is hung from said main shaft 11 and on the same shaft with said pulley 26 is a smaller pulley 260 over which an endless band runs to a band wheel 28 on said main shaft 11, an idler pulley 270 being mounted on said swinging frame or arm 27 to take care of slack in the band that runs to said pulley or band wheel 28 on said main shaft 11. A rod 190 having a yielding or spring section 191 connects the swinging arm 27 and the yoke 19.

For supporting a stile for a slitting operation, a table 29 in the form of an oblong plate is pivotally mounted by means of a horizontal bolt 290 on a horizontal extension or bracket 291 of said yoke 19, said table 29 being normally and yieldingly held in a position above said slitting saws 23 by springs 292. The table 29 is provided with two slots, one for each slitting saw through which said saws 23 pass when said table 29 with the stile to be slit thereon, is swung downward. Projecting outwardly from the outer end of said table 29 is a rod or bar 294 (which may be a piece of pipe) to which is secured an upwardly extending block 295 from one side of which a rod 296 (which likewise may be a piece of pipe) projects parallel with said rod 294 and said table 29. Said block 295 forms a gage to fix the position of the stile lengthwise by the contact of the stile with said block 295 so that the slits will be made in the stile the right distance from the end thereof. To the top of the table 29 is screwed an adjustable gage 297 to fix said stile in proper position upon the table 29 with its end portion lying beneath said rod 296. If the opposite end of the stile be pressed downward, the stile, supported by the table, will be carried downward on to the saws 23 and the two longitudinal slits made in the stile. As soon as the slitting is finished, upon releasing the stile, said table 29 will rise automatically from said slitting saws 23.

Besides carrying the slitting saws 23, the mandrel 22 carries a dado cutter, preferably one at each end of the mandrel, so that the operation of forming dadoes or rabbets in the stiles for the sills may be performed, the provision of two dado cutters enabling the simultaneous cutting of rabbets or dadoes in two stiles at the same time, during which operation the stiles are suitably clamped and supported, as hereinafter more

fully described. The dado cutter, as we prefer to construct it, consists of a cylindrical head 290^a from which projects, parallel with the mandrel axis, two similar arc-shaped blades which on their curved edges have cutting teeth 291^a and at one end, which is the forward end in the revolution of the dado cutter, each flange has an obliquely arranged chisel edge which by a longitudinal slit 292^a contiguous to the head 290^a is made to stand or project outwardly beyond the plane of the periphery of said head so that for a portion of its length the cutting blade thus formed by the flange is spirally curved. Since the dadoes or rabbets are cut at a slight incline to suit the inclination of the sill in the stile, the yoke 19 is inclined slightly from the vertical so that the dado cutters will move in a path inclined slightly from the vertical, and the pitch may be adjusted the yoke being pivoted on a horizontal shaft 197 and adjusting screws 192 being provided.

At its top, each side frame 10 has near each end a horizontally adjustable plate 30, with a series of step-like lugs 301 each of which lugs, in succession may, by the adjustment of the plate 30, serve as a support on which a stile rests during the dado cutting as well as during the performance of the operation of cross cutting the ends of the pockets, as hereinafter more fully set forth. The stile being operated on rests on the alining lugs 301 of the two plates 30 on one edge, and it is held against lateral movement by a pair of clamps at each end of the frame side 10. Each pair of clamps consist of a fixed jaw 31, and a movable jaw 32 having set screws 33 for impingement against the side of the stile, and attached at its lower end to a longitudinally extending rock shaft 34 journaled in bearings in the frame side 10. It will be seen that the set screws 33 afford means of using the clamps for stiles of different thickness, and when once adjusted for use with stiles of a particular thickness, a clamping and unclamping operation involves merely the rocking of the movable jaws 32 toward or from their companion fixed jaws 31, and to facilitate this operation, as well as enable the simultaneous operation of the clamps at both sides of the machine, the two movable jaws 32 at the same end of the machine are provided with crank arms 35, which are connected by toggle links 36, one of which is provided with a handle 37, by means of which the movable jaws 32 may be moved to and from the clamping position. The pin or bolt connecting the toggle levers is projected to engage a vertical guide-groove 360 in the adjacent frame end.

Extending transversely of the machine from one side frame to the other near the top thereof is a shaft 38 on which are

mounted four similar oscillating or rocker frames 39, consisting each of three arms, the form of the frame being thus T-shape. At the outer end of each horizontally extending 5 arm is a saw blade receiving socket 40, in which a cross-cutting saw blade 41 may be clamped by a set screw 42, and at its lower end the vertical arm is forked or bifurcated to straddle and engage an eccentric 43 on 10 the main driving shaft 11, so that by the rotation of the eccentric the saw-carrying frame will be oscillated, and the saw caused to cut cross wise of the stile resting upon the supporting plates 30 and held by the 15 clamping jaws 31—32 herein-before described in connection with the dado cutters. To feed said cross-cutting saws 41 during a cutting operation, their carrying and vibrating frames are laterally movable, and 20 said frames are arranged in pairs so that the operation of cross-cutting may proceed from both sides of a stile, and this, of course, requires that the frames of a pair shall move toward each other during a cutting operation and away from each other after such 25 operation has been performed. To effect the desired lateral movement of the frames automatically, those two frames of a pair whose movements occur simultaneously in 30 the same direction are connected by a cross bar 44, which has a lateral stud or projection 45 that is engaged by a cam 46 on the yoke-operating shaft 16, the cam acting to move the saw-carrying arms during a cutting operation, while to move said arms in the opposite direction, there is provided a coil 35 spring 47 connected to the frames. The cams 46, of course, are arranged to act reversely.

40 It will be seen that by means of a machine embodying our invention, the operations of cross-cutting the stiles to form the ends of the pockets, and the operation of dadoing or rabbeting the stiles are simultaneously performed upon two stiles. The 45 advantage of our machine, therefore, in respect to rapidity of doing the work, due both to the saving of carrying the material from one machine to another, and the simultaneous performance of a number of operations with one setting of the work, and the saving of floor space in having one machine 50 perform several operations will be apparent.

55 As showing the possibilities of the machine, it may be added that boring bits, emery wheels, and numerous other tools may be attached to the shaft or mandrel 22 in place of the dado heads, and wabble saws may be placed on the mandrel for plowing 60 and rabbeting window and door frames, etc.

What we claim is—

1. The combination of a frame having a support for a window frame stile, cross cutting saws mounted on said frame contiguous to the stile support at opposite sides

thereof and movable simultaneously toward each other for a cutting operation, a rotating cutting tool movably mounted on the frame contiguous to the stile support, the movement of said tool being crosswise of a 70 stile on the support, said saws and tool being situated to act upon the same stile, the saws and tool being spaced apart so as to act upon separated portions of the stile, and means for effecting the simultaneous operations of 75 said saws and tools.

2. The combination of a frame having a pair of supports for window frame stiles, cross cutting saws for each stile mounted in sets on the frame contiguous to the stile 80 support at opposite sides thereof and movable simultaneously toward each other for a cutting operation, a rotating cutting tool for each stile, a carrier for both tools movable in a space between the stiles on their 85 supports, and means for effecting the simultaneous operations of said saws and tools.

3. The combination of a support for a window frame stile, an oscillatory and laterally movable saw carrying frame for saws 90 adapted to cross cut a stile on the support, a reciprocating yoke, and a rabbeting tool carried by said yoke in position to act upon a stile on said support.

4. The combination of a stile support, a 95 pair of saw-carrying frames having each oppositely extending arms adapted to hold saws for acting upon opposite sides of a stile on the support, a pivotal support for said frames from which said arms extend, 100 and means for moving the frames laterally upon said support.

5. The combination of a pair of stile supports, a pair of saw-carrying frames having each oppositely extending arms adapted to 105 hold saws for acting upon opposite sides of a stile on the supports, a pivotal support for said frames from which said arms extend, means for moving the frames laterally upon said supports, and connections between 110 certain of said frames whereby they may be simultaneously moved laterally.

6. The combination of a frame having a pair of stile supports, each support adapted to support a stile, a pair of saw-carrying 115 frames on opposite sides of each support, a shaft upon which all of said frames are mounted, frame oscillating means comprising a shaft having an eccentric that engages a frame arm, a connection between each inner frame of a pair and the outer frame of the other pair, whereby the inner and outer frames of the two pairs are connected for lateral movement simultaneously and in the same direction, and means for moving the 120 frames parallel with the axis upon which they rock or oscillate.

7. The combination of a main driving shaft, a reciprocating yoke, connections between said yoke and said main shaft, a man- 130

mandrel carried by said yoke, saws and cutter heads on the mandrel, oscillatory and laterally movable saw-carrying frames adapted to hold saws in position to act on the work simultaneously with the cutter heads on the mandrel, and connections between said frames and said main shaft.

8. The combination of a main frame having opposite sides each of whose tops forms a stile support, two pairs of saw-carrying frames pivoted between the ends of said frame sides, the frames of a pair being situated on opposite sides of a frame side, means for oscillating said frames and for moving

them laterally parallel with their axis of oscillation, a yoke carrying a saw mandrel, a support for the yoke in which the yoke is vertically slidble, said support being at one end of the main frame, and means for imparting vertical movement to said yoke. 15
20

In testimony that we claim the foregoing we have hereunto set our hands.
